SURGICAL GOWNS

Daniel Tames, Chicago, Ill.

Application June 6, 1955, Serial No. 513,414

1 Claim. (Cl. 2—114)

This invention relates to surgeon's gowns of the type worn when performing a surgical operation. More particularly, it is directed to a novel garment of this type readily adaptable for wear by surgeons having different clothing size requirements and incorporating special features whereby its sleeves and other parts may be effectively kept in adjusted position.

Surgeon's operating gowns are usually donned from the front, having a back opening closed by draw strings or other suitable fastening means. Various sizes of these gowns must be kept on hand in the operating room to accommodate surgeons of differing physiques. This not only involves a considerable investment but also requires time and attention to locate the right size of gown for a particular surgeon. Additionally, it is difficult to keep the garment neatly in position on the wearer to prevent loose folds, baggy sleeves and the like from interfering with the surgeon's movements or contacting exposed portions of the patient's anatomy.

To this end, the present invention is directed to a novel surgical gown incorporating panels or sections including elastic cords or threads. By contraction or expansion (stretching) of these panels or sections, the gown may be conformingly fitted to persons of different sizes and physiques. Thereby, one of the invention gowns may replace several different size surgeon's gowns, considerably reducing the necessary inventory of such gowns.

As a further feature, the sleeves of the present gown are provided with elastic sections, such as elastic bands substantially midway of the forearm and upper arm portions, and elastic strips extending lengthwise of the sleeves. Thereby, when a sleeve is pulled up the arm, it is effectively maintained in adjusted position so as not to slide down at an inauspicious moment and interfere with a surgical manipulation or contact the patient's body.

For an understanding of the invention principles, reference is made to the following description of typical embodiments thereof as illustrated in the accompanying drawings.

In the drawings:

Figs. 1 and 2 are, respectively, front and back views of one form of surgical gown embodying the invention;

Figs. 3 and 4, respectively, front and back views of another embodiment of the gown; and

Fig. 5 is a front elevation of a sleeve illustrating a modified form of the gown shown in Figs. 3 and 4.

Referring to Figs. 1 and 2, a surgical gown 10 embodying the invention is shown as having a fully closed front 11 including a collar 12, a reinforcing panel 13 just below the collar, and a large front panel 14. Seams 16 extend across the front and around the back define a hem or the like receiving a draw string 15. A second draw string 17 extends through collar 12.

The draw strings 15 and 17 have their ends exposed at the rear of the garment so that, by overlapping edges 18 of open back 20, the back may be closed by tying drawstrings 15 and 17. As is known, this type of gown is

donned from the front, being usually held by a nurse or other assistant while the surgeon extends his arms through the sleeves 25 of the garment. The assistant then ties the garment at the back, so that no fastening means appear at the front of the garment to interfere with the surgeon's manipulations.

Sleeves 25 are stitched into the usual sleeve openings by seams 21, and have preferably rib-knitted cuffs 22 at their outer ends for gripping the wearer's wrist just above hand 23.

In accordance with the invention, an elastic strip 30 is formed along each sleeve, as by stitching therealong elastic threads 31 in the stretched condition. Strips 30 extend the full length of the sleeves from cuffs 22 to the upper ends of the sleeves, and the elastic threads 31 are anchored to the sleeve material at frequent intervals along the sleeve. In addition, a similar elastic strip or band 35 extends across the front 11, being formed of elastic threads 36 stitched to the material of the front in stretched condition and anchored thereto at frequent intervals.

When the surgeon dons the gown 10, the elastic strips 35 contract to hold the gown closely to the body at the chest level and without any projecting folds. The gown material is "tucked" into small pleats by the contracting strips 35.

The elastic strips 30 on sleeves 25, being stretched when the sleeve is fully extended, continually exert an upward pull on cuffs 22. Consequently, should the surgeon push the cuffs 22 up to bare his forearm 24 the strips 30 effectively maintain the sleeves 25 above the elbow. Thus, no attention is needed to hold the sleeves 25 retracted.

The strips 30, in addition, accommodate the sleeve length to arms of different length, thus adapting the gown for use by surgeons of different sizes. This fitting of different sized persons is further facilitated by the girth elastic strips 35.

Except for its sleeve construction, the gown 10' of Figs. 3 and 4 is similar to gown 10 of Figs. 1 and 2, and corresponding parts have been given the same reference characters primed.

In this form of the invention, the elastic strips 30 are replaced by elastic sections 40 in each sleeve 25', these sections being intermediate of the forearm and constituting elastic bands extending around the sleeve. Strips 40 are formed of elastic threads 41 extending around the sleeve and stitched to the material thereof at frequent intervals. The strips 40 perform the same ultimate function as strips 30 of Figs. 1 and 2 in maintaining the sleeves firmly in adjusted position on the arm.

As shown in Fig. 5, elastic band 40 may be supplemented or replaced by a similar elastic band 45 located midway of the upper arm portion and likewise formed by stitching elastic threads or cords 46 to the sleeve material at frequent intervals.

While specific embodiments of the invention have been shown and described in detail to illustrate the application of the invention principles, it will be understood that the invention may be embodied otherwise without departing from such principles.

What is claimed is:

A surgeon's operating gown comprising in combination, a front section, a pair of back sections having free adjacent edges, fastening means for closing said back sections when the gown is donned from the front thereof, a pair of sleeves extending from sleeve openings in said sections, said sleeves each terminating in a rib-knitted cuff for gripping the wearer's wrist just above the hand, each sleeve being provided with an elastic strip extending from the cuff to the shoulder portion of the gown, said

elastic strip comprising elastic threads which are stretched in the normal extended position of the sleeve, thereby constantly exerting an upward pull on the cuff, whereby upon occasion to bare the forearm, the corresponding strip effectively maintaining the corresponding cuff above the elbow, upon pushing the cuff to such position.
